GARMENT COVERING DEVICE

Robert P. Ingraham, San Antonio, Tex.

Application November 19, 1946, Serial No. 710,915

12 Claims. (Cl. 226—18)

1

This invention relates to garment covering, and more particularly to an improved method and apparatus for conveniently and expeditiously placing a garment bag about a garment or garments.

It is a common practice at present for an operator to manually place a garment bag on a vertically suspended rod so that the rod extends through the opening formed in the closed top of a conventional garment bag and into the bag. The operator first moves the bag upwardly on the rod with one hand, and then with the other hand suspends a garment which is supported on a conventional hanger on the hook provided at the lower terminal of the rod. After the garment has been suspended, the operator then employs both hands to pull the bag down over the garment.

It is an object of this invention to provide means for automatically elevating a conventional garment bag on a vertical guide sufficiently to permit a garment supported by a conventional hanger to be suspended from the lower terminal of the guide, and then automatically dropping the bag onto the suspended garment.

Another object of this invention is to provide means for automatically inflating a conventional garment bag to open it and simultaneously move the inflated bag upwardly along a vertical guide sufficiently to permit a garment supported by a conventional garment hanger to be suspended from the lower terminal of the guide, and then automatically dropping the open bag onto the suspended garment.

A specific object of this invention is to provide an automatic garment covering device which includes a vertically suspended tube that is communicated with a source of air under pressure, means for directing air streams upwardly into a conventional garment bag which has been placed on the lower portion of the tube with the tube extending through the usual aperture formed in the closed top of the bag and into the bag to thereby raise the bag along the tube sufficiently to position the lower terminal of the bag above the lower terminal of the tube so that a garment may be suspended from the lower terminal of the tube, and means to discontinue the upwardly directed air streams after a garment is suspended from the tube to thereby permit the bag to gravitate onto the suspended garment.

A more specific object of this invention is to provide an automatic garment covering device which includes a vertically suspended tube communicated with a source of air under pressure,

2

a yieldable member operably supported at the lower terminal of the tube and cooperably associated with means for directing air streams from the tube upwardly into a conventional garment bag which has been previously placed on the lower portion of the tube with the tube extending through the usual aperture formed in the closed top of the bag and into the bag, the yieldable member being operable to discontinue the upward air streams when it yields responsive to the weight of a garment after the garment has been suspended from the yieldable member to thereby permit the bag to gravitate onto the suspended garment.

It is also an object of this invention to provide a garment covering device of generally improved construction, whereby the device will be simple, durable and inexpensive in construction, as well as convenient, practical, serviceable and efficient in its use.

With the foregoing and other objects in view, which will appear as the description proceeds, the invention resides in the combination and arrangement of parts, and in the details of construction hereinafter described and claimed, it being understood that various changes in form, proportion and minor details of construction may be made within the scope of the claims without departing from the spirit of sacrificing any advantages of the invention.

For a complete disclosure of the invention, a detailed description thereof will now be given in connection with the accompanying drawings, forming part of the specification, wherein:

Figure 1 is a side elevation of the garment covering device, parts being shown in section, depicting a conventional garment bag in the position in which it is placed by the operator and also in raised position;

Figure 2 is a similar view, depicting a garment bag in raised position and also in garment covering position;

Figure 3 is an enlarged fragmental vertical sectional view taken through the lower terminal of the air tube and deflecting cup, depicting the sliding sleeve in its raised or open position; and

Figure 4 is a similar view depicting the sleeve in its lowered or closed position.

Referring to the drawings, in which similar reference characters designate corresponding parts, 10 indicates a ceiling or other suitable support to which a bracket 11 is secured, and the bracket, in turn, supports an air blower 12 which is preferably driven by an electric motor 13. The blower is of the well known construc-

tion in which air is drawn in at the center of the blower casing and discharge through a tangential peripheral outlet member 15.

The outlet member 15 as a guide in the form of an air tube or conduit 16 attached thereto and suspended therefrom. This tube extends downwardly to a point within convenient reach of an operator standing on the floor of the structure which supports the ceiling 10. A pin or rod 17 extends transversely through the tube at a point adjacent its lower terminal, and this pin receives the eye of a helical extension spring 18. A similar eye is formed at the opposed terminal of the spring 18, and this eye engages a hook 20 which is secured to a pin 21 that is carried by a slideable sleeve or control valve 22. A similar pin 23 extends transversely across the sleeve adjacent its lower terminal, and this pin, in turn, has a hook 25 depending therefrom. By this arrangement, the sleeve 22 is normally held within the tube 16, and the upward or inward movement of the sleeve 22 within the tube 16 may be limited by a stop member or screw 26.

The lower terminal of the tube 16 extends downwardly an appreciable distance into a semi-spherical cup or deflecting member 27, and the cup is preferably secured to the lower terminal of the tube 16 by suitable brackets 28. It is to be understood, of course, that other means may be employed to secure the cup in correct relation to the tube 16.

The inner surface of the cup 27 preferably has an annular valve seat 30 formed therein in axial alignment with the lower terminal of the air tube 16. The hook 25 extends through an aperture 31 formed in the cup 27 in alignment with the axis of the air tube 16. By this arrangement, the shank 32 of the hook 25 slides axially within the aperture 31 when the sleeve 22 moves axially within the air tube 16. A yieldable gasket or packing ring 33 preferably surrounds the upper terminal of the hook shank 32, and this gasket is arranged to cooperably engage the inner wall of the cup surrounding the aperture 31, for a purpose which will hereinafter be set forth.

In the operation of the device, the electric motor 13 drives the blower, thereby directing a stream of air downwardly through the tube 16. The slideable sleeve is normally held within the tube against the stop 26 by the spring 18, thus permitting the stream of air which flows downwardly through and from the tube 16 to impinge the inner surface of the cup 27 where it is deflected or reverted upwardly between the upper terminal of the cup and the surrounded lower terminal of the tube 16. Thus it is seen that when the slideable sleeve valve 22 is in its normally retracted position, as shown in Figure 3, a stream of air is constantly reverted upwardly from the cup 27 around the tube 16.

In the use of the device, an operator places a conventional garment bag or sack B on the lower portion of the air tube 16 so that the cup 27 passes through the aperture 31 customarily formed in the center of the closed top 36 of the bag, as indicated in full lines in Figure 1. After the bag B has been placed on the tube 16 so that its closed top 36 is above the cup 27, the bag is then inflated and moved upwardly along the tube 16 by the reverted air stream until the lower open end of the bag B is appreciably above the lower terminal of the tube, as indicated in dot and dash lines in Figure 1. The inflation of the bag B maintains it in open or extended condition to more readily receive the garment.

Now the operator suspends the garment G, supported on the conventional garment or clothes hanger H, from the slideable sleeve 22 by engaging the hook of the garment hanger H with the hook 25 carried by the sleeve 22. The weight of the garment causes the sleeve 22 to slide downwardly against the tension of the spring 18 until its lower terminal engages the valve seat 30. At the same time the soft, yieldable gasket 33 covers the aperture 31 through which the shank of the hook slides, thus confining the air to the tube 16. This permits the raised and inflated bag B to drop by gravity onto the garment and cover said garment for the usual service distribution. If the bag should not drop far enough to completely cover the garment, the operator may then conveniently draw the bag completely over the suspended garment, and the open condition of the bag facilitates this manual operation.

The covered garment is then removed from the hook 25 preparatory to subsequent use of the device. When the garment is removed, the spring 18 draws the sleeve valve 22 into the tube 16 against the stop 26, thus communicating the interior of the tube with the interior of the cup 27 so that a stream of air is again reverted upwardly around the tube, thereby conditioning the device for further use.

I claim:

1. The method of covering a garment with a garment bag having an open bottom and a closed top with an aperture formed therein, which includes placing the garment bag on a suspended guide so that the lower terminal of the guide extends through the aperture into the bag, directing air streams upwardly into the bag to move the bag upwardly on the guide, supporting the garment at the lower terminal of the guide and then discontinuing the upward air streams to thereby permit the bag to gravitate onto the garment.

2. The method of covering a garment with a garment bag having an open bottom and a closed top with an aperture formed therein, which includes placing the garment bag on a suspended conduit so that the lower terminal on the conduit extends through the aperture into the bag, directing an air stream downwardly through the conduit and then reverting the air stream upwardly into the bag to fully open the bag and move it upwardly on the conduit, supporting the garment at the lower terminal of the conduit and discontinuing the upward air stream to thereby permit the open bag to gravitate onto the garment.

3. A garment covering device including a suspended guide, means for directing air streams upwardly from the lower terminal of the guide into a garment bag movably supported on the guide to thereby move the bag upwardly along the guide, and means for discontinuing the air streams to permit the bag to gravitate along the guide onto a garment supported at the lower terminal of the guide.

4. A garment covering device including a suspended guide tube communicated with a source of air under pressure, a control valve at the lower terminal of the tube and operable to permit an air stream to flow downwardly from the lower terminal of the tube, means adjacent the lower terminal of the tube to revert the air stream upwardly around the tube into a garment bag movably supported on the tube to thereby move the bag upwardly along the tube, the control valve being operable to discontinue the upward air stream thereby permitting the bag to gravitate onto the garment.

tate onto a garment supported at the lower terminal of the tube.

5. A garment covering device including a suspended guide tube communicated with a source of air under pressure, a yieldably-supported valve at the lower terminal of the tube and operable to permit an air stream to flow downwardly from the lower terminal of the tube, means to revert the air stream upwardly from the lower terminal of the tube and around the tube into a garment bag movably supported on the tube to thereby move the bag upwardly along the tube, means for detachably suspending a garment from the valve, the valve yielding responsive to the weight of the suspended garment to closed position to discontinue the upward air stream thereby permitting the bag to gravitate onto the suspended garment.

6. A garment covering device including a suspended guide tube communicated with a source of air under pressure to force the air downwardly through the tube, a control valve at the lower terminal of the tube and operable to permit an air stream to flow downwardly from the lower terminal of the tube, means adjacent the lower terminal of the tube to revert the air stream upwardly around the tube into a garment bag movably supported on the tube to thereby move the bag upwardly along the tube, the control valve being operable to discontinue the upward air stream thereby permitting the bag to gravitate onto a garment supported at the lower terminal of the tube.

7. A garment covering device including a suspended guide tube communicated with a source of air under pressure to force the air downwardly through the tube, a yieldably-supported valve at the lower terminal of the tube and operable to permit an air stream to flow from the lower terminal of the tube, means to revert the air stream upwardly from the lower terminal of the tube and around the tube into a garment bag movably supported on the tube to thereby move the bag upwardly along the tube, means for detachably suspending a garment from the valve, the valve yielding responsive to the weight of the suspended garment to closed position to discontinue the upward air stream thereby permitting the bag to gravitate onto the suspended garment.

8. A garment covering device including a suspended tube, an air blower communicated with the tube and operable to force air downwardly through the tube, a control valve at the lower terminal of the tube and operable to permit an air stream to flow downwardly from the lower terminal of the tube, means adjacent the lower terminal of the tube to revert the air stream upwardly around the tube into a garment bag movably supported on the tube to thereby move the bag upwardly along the tube, the control valve being operable to discontinue the upward air stream thereby permitting the bag to gravitate onto a garment supported at the lower terminal of the tube.

9. A garment covering device including a suspended tube, an air blower communicated with the tube and operable to force air downwardly through the tube, a yieldably-supported valve at the lower terminal of the tube and operable to permit an air stream to flow from the lower terminal of the tube, means to revert the air stream upwardly from the lower terminal of the tube and around the tube into a garment bag movably supported on the tube to thereby move the bag upwardly along the tube, means for detachably suspending a garment from the valve, the valve yielding responsive to the weight of the suspended garment to closed position to discontinue the upward air stream thereby permitting the bag to gravitate onto the suspended garment.

10. A garment covering device including a suspended tube communicated with a source of air under pressure, a sleeve valve axially slidable within the tube and operable to permit an air stream to flow downwardly from the lower terminal of the tube, a cup supported to surround the lower terminal of the tube and operable when communicated with the tube to revert the air stream upwardly into a garment bag movably supported on the tube to raise the bag along the tube, means for yieldingly supporting the sleeve valve in position to communicate the tube with the cup, a hook suspended from the valve to detachably support a garment carried on a garment hanger, the weight of the garment moving the valve to position to sever communication between the tube and the cup to discontinue the reverted air stream thereby permitting the bag to gravitate onto the garment.

11. The method of covering an object with a covering bag having one end open and the other closed, which includes introducing air under pressure to the interior of the bag to inflate and move the bag against gravity in a linear direction simultaneously, supporting the object in the space vacated by the bag and adjacent the open end of the latter, and then discontinuing the air pressure to release the bag to the action of gravity.

12. The method of covering an object with a covering bag having one end open and the other closed, which consists in introducing air under pressure to the interior of the bag to inflate and to simultaneously move the bag in an upward direction and against the action of gravity, supporting the objects in the space vacated by the bag and adjacent the open end thereof, and then discontinuing the air pressure within the bag.
